METHOD OF MAKING FASTENER SLIDERS

Didrick Dyresen, Billerica, Mass., assignor to
United-Carr Fastener Corporation, Cambridge, Mass., a corporation of Massachusetts

Application July 21, 1934, Serial No. 736,368

4 Claims. (Cl. 29—148)

My invention aims to provide improvements in the method of making sliders for use with multiple fasteners.

In the drawing, which illustrates a preferred embodiment of my invention:

Figure 1 is an elevational view of a portion of a multiple operable fastener installation showing a slider made by my improved method;

Fig. 2 is a side elevation of the slider;
10 Fig. 3 is a plan view of a portion of a strip showing the method of forming the reinforcing rib;

Fig. 4 is a plan view of a portion of the strip showing the method of forming and blanking the 15 slider body after the reinforcing rib has been formed;

Fig. 5 is a side view of the blank as it appears when cut from the strip;

Fig. 6 is a section of the slider taken on the line 20 6—6 of Fig. 1; and

Fig. 7 is a section of the slider taken on the line 1—1 of Fig. 2.

Referring now to the slider selected for illustration of my invention, I have shown, in Figs. 1 25 and 2, a slider constructed by my improved method hereinafter described. The slider has a body formed from a single piece of sheet metal without the use of rivets or other pieces to stiffen and strengthen the body as has been necessary here-

30 tofore. The particular slider illustrated has a top plate portion 1 and a bottom plate portion 2 spaced a predetermined distance from the top plate portion. Each plate portion has its side edges turned at substantially right angles to form

35 flanges 3 facing each other and spaced slight distances apart to permit passage of the stringers 4 and 5, when the slider passes over the fastener elements 6 shown in Fig. 1. The plate portions 1 and 2 are joined together at one end by a hollow

40 rib 7 which is more or less U-shaped and extends at least part way along the outer faces of the plate portions 1 and 2. This rib has sides which are preferably flat and relatively close together, thereby stiffening the slider body so that the

45 plate portions 1 and 2 are held in fixed planes as against any ordinary stresses which may be exerted upon them in use. That portion of the rib 7 located at the bottom of the slider, or in the bottom plate portion 2, is less pronounced than

50 at the top side thereby overcoming any objectionable projection on the inner side of an installation to which the device is to be applied. The rib portion at the top plate 1 may serve as a means to receive and hold the usual pull tab 8,

as shown in Figs. 1 and 2.

The plate portions are wider at the end where they are joined together by the rib than they are at their free ends (Fig. 7). This is for the purpose of providing for the necessary diverging channels. Cooperating with the flanges 3 to form 5 these channels are a pair of projections 8 extending from the rib toward the other end of the slider body. I have tapered these projections so that when they are bent together they form a comparatively sharp edge which greatly aids the 10 operation of the slider:

In Figs. 3 and 4, I have illustrated portions of a strip of sheet metal, such as is used in the manufacture of my invention, and clearly showing the successive steps in the forming of the slider. 15

Beginning at A (Fig. 3) and proceeding through D, the steps consist of simple drawing operations which form the rib 7, in this illustration extending downwardly from the visible side. Step E is the final drawing operation upon the rib and 20 includes swaging a pair of depressions on opposite sides of the rib which later form the projections 8. These depressions become regularly deeper toward their outer ends and are deepest at their ends. The next step F consists in piercing the holes 9, which mark the free ends of the plate portions 1 and 2 and leave a small connecting link 10 between the slider blanks so that they 25 may be fed in a strip through the press. In operation F I also pierce out the portions 11, thereby delineating the ends of the plates 1 and 2 which are adjacent to the neck portion when the slider is completed. It will be noticed that one 30 end of the rib is tapered to a comparatively thin point. This is the end that lies along the back plate. It also extends further toward the free end of the slider than the rib on the other plate. This is because it is necessary to have a more pronounced projection on the front plate for the purpose of attaching the pull member. This piercing operation also cuts away the portions of the strip around the depressions leaving the projections 8, which taper toward their free ends as 35 described above. In step G, I commence the forming of the side flanges 3. This is a combined drawing and bending operation which results in making the flanges thinner than the plates when finished. After the first flange-forming operation as at G, the sides of the plate portions 1 and 2 are freed by the blanking operation as at step 40 H. During this operation the flanges 3 are completed. At step I, the portions 12 of the rib, between the projections 8 and the plate portions are swaged and curved toward each other until 45 they meet and form tubular portions at each side 50

55

of the projections. This is for the purpose of making the rib more rigid and of presenting a neater and more compact finished slider. The final operation in this particular series is that of separating the partly finished slider from the strip as at 13 in step J.

Now there remains the bending of the rib to make the plates 1 and 2 lie in parallel planes. This is done so that the plates exactly overlie one another and their flanges extend directly toward each other with a space between them to permit the passage of the fastener stringers. At this point the projections 8 are bent toward each other until they meet, their tapered ends forming a neat and smooth joint. The final step is that of sizing the slider to the very exact dimensions demanded by the nature of the task it is to perform. The pull-tab may be attached to the rib on the front face of the slider by any suitable method. I prefer to drill holes in the rib to receive the connecting link of the tab (Figs. 1 and 2).

The slider I have described is simple, sturdy and neat in appearance. By virtue of its rib it will resist unusual strains in all directions. The method I have invented for making the slider is novel and simple, easily and inexpensively performed.

While I have illustrated and described a form of my invention, I do not wish to be limited thereby, since the scope of my invention is best defined by the following claims.

1. The method of forming slider bodies of the class described having opposite spaced apart wings and means forming diverging channels comprising subjecting a strip of metal to a series of drawing operations to form a relatively narrow rib, blanking the strip to form the wings, each wing including a portion of said rib, piercing the strip at predetermined places with respect to said rib for forming the diverging channel-forming means, forming flanges on said wings, and bending the ribs between the wings until said wings lie in opposed spaced relationship.

2. The method of making a slider body of the class described which has opposed spaced-apart plate portions connected at one end of the slider by a stiffening rib which comprises subjecting a strip of metal to a series of drawing operations to form a relatively narrow rib, piercing the strip at predetermined places with respect to said rib, forming the plate portions adjacent to the opposite ends of said rib, blanking the slider body from said strip and then folding the blank at a point between the ends of the rib, thereby bring-

ing the plate portions into opposed spaced relationship.

3. The method of making a slider body of the class described which comprises subjecting a strip of metal to a series of drawing operations to form a hollow rib of suitable length extending longitudinally of said strip, said rib being relatively narrow, forming a pair of substantially rectangular depressions in said strip on opposite sides of said rib at a predetermined point between the ends of said rib, said depressions being deeper in the ends thereof remote from said rib, piercing a pair of apertures adjacent each end of said rib and spaced therefrom a predetermined distance, piercing said strip in such a manner adjacent said depressions as to leave a pair of relatively thin projections formed from the depressed portions and extending from opposite sides of said rib, blanking said strip to form the plate portions of the slider, said plate portions being located at opposite ends of the rib and each plate including a portion thereof, bending said thin projections toward each other on that side of the strip away from said rib, and bending the rib at a point between the plate portions so that said plate portions lie in parallel planes.

4. The method of making a slider body of the class described which comprises subjecting a strip of metal to a series of drawing operations to form a relatively narrow hollow rib of predetermined length extending lengthwise of said strip, blanking out portions of said strip to form a pair of projections extending from opposite sides of said rib at a point near the mid-portion thereof, delineating the plate portions of the slider so that they lie one at each end of said rib and each including a portion thereof and in the same operation commencing the formation of flanges along the opposite sides of said plate portion, blanking out further portions of said strip adjacent to the sides of said plate portions and completing the formation of said flanges, swaging the portions of the rib between the adjacent ends of said plate portions and said projections from the ribs so that a tubular portion is formed at each side of said projections and in the same operation bending said projections toward each other, cutting the slider blank from said strip and bending the rib at a point between the plate portions until the plate portions are in parallel planes, the flanges on said plate portions extending toward each other and the projections of the rib extending into the space between the plates.
